UNITED STATES PATENT OFFICE.

**JAMES H. SAGER, OF ROCHESTER, NEW YORK, ASSIGNOR TO J. H. SAGER COMPANY,
OF ROCHESTER, NEW YORK, A CORPORATION OF NEW YORK.**

DESIGN FOR A BASE MEMBER FOR AUTOMOBILE-BUMPERS.

45,570.

Specification for Design.

Patented Apr. 7, 1914.

Application filed February 5, 1913. Serial No. 746,371. Term of patent 7 years.

To all whom it may concern:

Be it known that I, JAMES H. SAGER, a citizen of the United States, residing at Rochester, in the county of Monroe and State of New York, have invented a new, original, and ornamental Design for a Base Member for Automobile-Bumpers, of which the following is a specification, reference being had to the accompanying drawings, forming part thereof.

In the drawings: Figure 1 is a side-elevation of a base-member for an automobile-

bumper, in accordance with the present design; and Fig. 2 is a perspective view of the same part.

I claim:

The ornamental design for a base-member for an automobile-bumper as illustrated in said drawings.
